United States Patent Office.

H. E. GILLET, OF OSWEGO, NEW YORK.

Letters Patent No. 96,100, dated October 26, 1869.

IMPROVED FOLDING DESK AND SEAT.

The Schedule referred to in these Letters Patent and making part of the same.

To all whom it may concern:

Be it known that I, H. E. GILLET, of Oswego, in the county of Oswego, and State of New York, have invented a new and useful Improvement in Folding Seat and Desk; and I do hereby declare that the following is a full, clear, and exact description thereof, which will enable others skilled in the art to make and use the same, reference being had to the accompanying drawings, forming part of this specification.

This invention relates to improvements in folding desks and seats for schools, having for its object to provide an improved arrangement of the joints upon which the seat-arms oscillate; an improved arrangement for simultaneously disconnecting the braces of the desk, for folding it down, whereby one person may conveniently fold down desks of any length.

Figure 1 represents an end elevation of a desk constructed according to my improvements;

Figure 2 is a transverse sectional elevation;

Figure 3 is a partial rear elevation of the same; and

Figure 4 represents a sectional elevation of the joint of the seat-arm.

Similar letters of reference indicate corresponding parts.

A represents the end supports;

B, the back, rigidly attached thereto;

C, the folding seat; and

D, the folding desk.

The seat is secured to the arms E, which I prefer to make of considerable breadth, in the direction at right angles to the seat, for the purpose of supporting a board or other plate, F, to form a book-case.

The said arms E are pivoted to the end supports at G, and have a rear extension, I, and lugs at the end thereof, which take under ledges K when folded down to maintain the seat in the right position for sitting thereon, as represented in figs. 1 and 2.

In order to prevent the seats from being suddenly thrown down, endangering the breakage of the arms, and making unnecessary noise, I provide a friction-joint for the pivot G, as follows:

L represents a stud, projecting from each end support at the point where the hole is formed for the pivot-bolt M, and the said hole is preferably made square for a certain portion of its length, or it may be the whole length, to prevent the turning of the bolt, and the washers forming the friction-joint.

The arms are fitted to work on the said studs, and slight projections N formed thereon around the holes to constitute the bearing-surfaces between the said arms and the end supports A, and a frictional pressure is maintained on the arms, between the end supports and a washer, O, by a yielding washer, Y, of rubber,

or other similar substance, interposed between the said washer O and another metallic washer, P, on the shank of the bolt at the head.

This arrangement provides a large bearing-surface for the holes through the seat-arms, and admits of adjusting the pressure by the bolt M and its nut to any required degree, and to compensate for wear.

Instead of rubber washers, elliptic or spiral springs may be used.

The bolt and the washers forming the friction-joint, being prevented from turning, relieve the tendency of the metallic washers to split the rubber washers by the unequal movements of the former on either side of the latter; also the loosening of the tightening-nut on the bolt M.

The said desks D are hinged at the tops in the usual manner, and provided with the braces O, hinged thereto at R, and provided with studs S at their lower ends, which fall into and rest in the notches T in the upper ends of the slots U, when the desks are raised up, and thereby maintain the desks in the elevated position.

When it is desired to fold the said desks down, the studs S are raised out of the said notches, and slide down in the slots U.

As these desks are sometimes made of considerable length, rendering it inconvenient for one person to raise both braces at once, to fold them down, I have provided the crank-shaft V, extending from one end-support to the other, and provided with the tappets W and a hand-crank, X, so arranged, that by turning the shaft in the right direction by the hand-crank, the said tappets will strike the lower ends of the arms O and raise their studs S out of the notches T, simultaneously at each end, whereby one person may readily fold them down, no matter how long they may be.

Having thus described my invention.

I claim as new, and desire to secure by Letters Patent—

1. The improved friction-joint for the seat-arms, consisting of the hub L, of the end supports, whereon the arms are suspended, the metallic washers O and P, the yielding washer Y, and the bolt M, all arranged as and for the purpose specified.

2. The combination, with the braces O and the end supports A, of the crank-shaft V, having the tappets W, as and for the purpose specified.

The above specification of my invention signed by me, this 1st day of December, 1868.

H. E. GILLET.
